(57) **CLAIM**

The ornamental design for wrench, as shown and described.

DESCRIPTION

FIG. 1 is a perspective view of wrench showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top side elevational view thereof;

FIG. 7 is a bottom side elevational view thereof; and,

FIG. 8 is a perspective view embodying the utilization of my new design.
The broken lines shown in FIG. 8 for illustrative purposes only and form no part of the claimed design.
